UNITED STATES PATENT OFFICE.

EDWIN R. CAHOONE, OF NEWARK, NEW JERSEY.

DESIGN FOR METAL JOCKEY FOR SADDLE-TREES.

Specification forming part of Design No. 11,246, dated June 17, 1879; application filed May 8, 1879.
[Term of patent 14 years.]

To all whom it may concern:

Be it known that I, EDWIN R. CAHOONE, of Newark, in the county of Essex and State of New Jersey, have originated and designed a new and Improved Design for Metal Jockey for Saddle-Trees, of which the following is a full, clear, and exact description, reference being had to the accompanying drawing, making part of this specification.

This invention relates to a new and original design of a metal jockey for saddle-trees; and consists, principally, in the production of a metal jockey having cast in the frame imitation tuft-nails, instead of having holes for the reception of the ordinary tuft-nails.

Usually the tuft-nails are put through holes in the jockey-flaps; but the improvements in the manufacture of saddle-trees have rendered the use of such nails as fastening devices unnecessary.

In the drawing, the letters *a* designate the imitation tuft-nails, and *b* and *c* are ornamental depressions cast in the flap part of the jockey, and run around near its edge. The object of these depressions is to impart an ornamental appearance and finish to the jockey, the distinctive feature of this invention being the imitation tuft-nails *a*.

What I claim as my invention, and desire to secure by Letters Patent, is—

A design for a jockey for saddle-trees, having the imitation tuft-nails *a*, substantially as above described.

EDWIN R. CAHOONE.
